HARRY J. WRIGHT, OF BLOOMFIELD, NEW JERSEY, ASSIGNOR TO HIMSELF, AND EDGAR L. SCILLITO, OF STAPLETON, NEW YORK.

DOOR CLOSER AND CHECK.

1,114,216.

Specification of Letters Patent.

Patented Oct. 20, 1914.

Application filed January 17, 1914. Serial No. 812,653.

To all whom it may concern:

Be it known that I, HARRY J. WRIGHT, a citizen of the United States, residing at Bloomfield, in the county of Essex and State of New Jersey, have invented a certain new and useful Improvement in Door Closers and Checks, of which the following is a specification.

The invention relates to that class of single-acting door-closers and checks in which the closing and checking mechanism is contained in a casing located in the floor or sill beneath the door, and known as floor-hinges.

The main object of the invention is to provide a simple mechanism adapted to serve with either right or left-hand doors without change, and by which the door when swung open to approximately 90° will be closed and checked when released, and when opened to a greater angle will swing automatically to approximately 180° and be checked in approaching the end of such swing.

Another important object is to provide means whereby the degree of opening or angle at which the door will be closed and checked may be varied to permit such opening swing to be more or less than 90° as may be desired.

The invention consists in certain novel features of construction and arrangement of parts by which the above objects are attained, to be hereinafter described and claimed.

The accompanying drawings form a part of this specification and show the invention as it has been carried out in practice, applied to a right-hand door.

Figure 1 is an elevation of a door equipped with the improved hinge. Fig. 2 is a corresponding plan view, partly in horizontal section. Fig. 3 is a side view of the floor hinge on a larger scale. Fig. 4 is a corresponding plan view with the cover removed. Fig. 5 is a longitudinal vertical section taken on the irregular line 5—5 in Fig. 6. Fig. 6 is a transverse section, on the line 6—6 in Fig. 5. Fig. 7 is a similar view taken on the line 7—7 in Fig. 5. Fig. 8 is a similar section, on the line 8—8 in Fig. 5. Fig. 9 is a diagrammatic plan view, corresponding to Fig. 4 but with certain portions omitted, showing the positions assumed by the parts at various points in the arc of the swing of the door. Fig. 10 is an elevation showing

the pivot members for the top of the door. Fig. 11 is a plan or face view of the same. Fig. 12 is a plan view of the arm or lever connecting the bottom of the door to the closing mechanism. Fig. 13 is an elevation, partly in vertical section, showing on a larger scale the means employed for varying the angle at which the door will be closed. Fig. 14 is a plan view of the same. Fig. 15 is a corresponding side elevation.

Similar letters of reference indicate the same parts in all the figures.

A is a right-hand door, supported by a lever B mortised into its lower edge, and having an offset socket B¹ receiving and resting upon the squared upper end of the vertical shaft C of the closing mechanism. Mortised in the top of the door is an arm A¹ having an offset A² corresponding to the socket B¹ below and drilled and tapped to receive the screwthreaded end of a pin A³ extending loosely through an offset A⁵ on a similar arm A⁴ let into the lintel above the door. The pin A³ and shaft C are in vertical alinement to serve as hinges, and the several offsets permit the door to close squarely against the door-stops A⁶ A⁶ and to swing clear of the door-casing when fully opened.

M is a box-like casing containing the closing and checking mechanism, set in the floor beneath the door, having a close-fitting flanged cover M¹ secured thereto by screws, and covered by an ornamental plate M², as usual, similarly secured. The lower end of the shaft C is stepped in a boss M³ in the bottom of the casing and extends through an opening m in the cover, serving as an upper bearing therefor. A tapered square C¹ at the upper end is received in the socket B¹ of the door-lever, as above described, and the shaft is partially rotated or oscillated by the swing of the door.

C² C² are arms at the midheight of the shaft, carrying a pin C³ on which is a roller C⁴ mounted between the arms, arranged to apply against the face of a slide D and move the latter longitudinally of the casing in opposition to the force of a helical spring E abutting at one end against a circular nut D² mounted on a screw D¹ carried by the slide, and at the other against a partial partition M⁴ in the casing. The nut D² permits the force of the spring to be varied as found necessary.

The slide D is guided by a central leg or projection D³ on the lower portion, received in a groove m¹ in the bottom of the casing and by the arms D⁴, one on each side at the top, lying beneath the guides M⁵ on the interior of the casing.

The vertical partial partition M⁶ with a horizontal deck M⁶ forms a liquid chamber m² at the end of the casing opposite the shaft C and entirely separated from the spring chamber. It is sealed by a screw-plug N in line with the longitudinally disposed checking cylinder M⁷ opening from the liquid chamber and receiving the checking-piston F which is provided with the usual valved passage f.

G is a vertical shaft or spindle extending through the liquid chamber m², stepped in the boss M⁸ and projecting through a stuffing-box M⁹ in the deck M⁶. A squared portion G¹ at the lower end receives a horizontal arm G² connected by a pitman G³ to the piston F and moves the latter as the spindle G is partially rotated. On the upper end of the spindle G is a square G⁴ receiving a crank G⁵ carrying a crank-pin G⁶ connected by a long link H to the projecting upper end of the pin G³ and communicates motion from the shaft C at one end of the casing to the spindle G at the other end.

A by-pass m³ from the liquid chamber m² to the space behind the piston F, controlled by the valve F¹, permits liquid to flow slowly from such space to the chamber as the piston is forced toward the closed end of the cylinder, and with the valved passage f in the piston, permits such liquid to flow freely in the opposite direction as usual when the movement of the piston is reversed.

Thus constructed and arranged, the opening movement of the door causes the roller C⁴ to move the slide D and compress the spring E, and at the same time, through the link H, partially to rotate the spindle G and move its connected piston, the liquid flowing freely through the latter and the by-pass to supply the space behind the piston, until the arms C² assume a position at a right angle or nearly so with the face of the slide D, in which position the door will be opened a little more than a right angle. If the door be then released the force of the spring E will return it to the closed condition, the reverse movement of the spindle G and its piston F checking such closing movement, but if the door be swung still farther in the opening direction the arms C² will pass the line of extreme movement of the slide, and the spring will exert its force to continue the opening movement and swing the door to an angle of approximately 180°, checking the movement as the door approaches the end of such swing and holding the door against the wall and substan-

tially parallel therewith, as shown in dotted lines in Fig. 2.

In closing the door from this position the first portion of the swing is opposed by the spring and uncheck, the last portion is aided by the spring and checked.

To position the device for service with a left-hand door, it is necessary only to swing the arms C² past the center line into the position corresponding but opposite to that shown in Fig. 4, and to reverse or turn over the lever B and the upper hinge members A¹ and A⁴, keeping A⁴ still uppermost. The mechanism will then act in all respects the same as before without further change. To facilitate the attachment of the lever B and members A¹ and A⁴ with either face uppermost, the screw openings a and b are countersunk from both sides, and the socket opening b¹ is tapered inwardly from both faces to match to the tapered square C¹ of the shaft C. A plane face B² at the socket end of the lever is designed to be placed flush with the inner edge of the door in both positions and aids in locating the lever properly. The upper members A¹ A⁴ are similarly shaped.

In order to initiate quickly the return movement of the slide and more particularly, to determine the point in the arc described by the door and arms C² at which the door will close when released or continue its opening movement under the pressure of the spring E, a transverse cam-plate J is mounted on the face of the slide next the shaft C to receive the thrust of the roller C⁴ and impart it to the slide. This cam-plate has a central ridge or elevation J¹ and a high point J² J³ at each end joined to the central ridge by intermediate concavely curved portions J⁴ J⁵ designed to so control the compression of the spring as to offer an approximately equal resistance to the movement of the door at all points in its swing, and the central ridge J¹ offers a determinate central point or position at which when the door is released the latter will be forced by the spring E either to close or to swing farther open, and should be so placed as to be reached or ridden upon by the roller when the door is swung to an angle somewhat greater than 90°, such as is usually produced by a person passing through the doorway. This location carries the ridge J¹ to one side of the longitudinal center line of the casing passing through the axis of the shaft C, and in positioning the hinge for service with a left-hand door it should be shifted to a corresponding position on the opposite side of such line. To permit such shifting, the cam-plate J is mounted to be moved transversely of the casing and locked in either position. On the face of the slide D are lugs D⁵ D⁶ arranged in pairs and undercut at an angle on the inner faces 130

to receive dovetailed ways J^4 J^4 on the margins of the cam-plate and permit the latter to slide therein, and the slide is provided with three semicircular vertical grooves j , j^1 and j^2 on its face adjacent to the cam-plate, which is provided with a centrally located semicircular groove d matching to either of the other grooves as presented thereto, thus forming a vertical cavity of circular section in which is received a cylindrical pin K serving to lock the cam-plate and slide in position relatively to each other.

When the central groove j is locked with the groove d the ridge J^1 is centrally presented and the point in the swing of the door at which it will be automatically closed and checked is 90° ; with the groove j^1 engaged the angle of such opening will be somewhat greater than 90° , as preferred for a right-hand door, and with the groove j^2 engaged the device will be conditioned for an opening swing correspondingly greater than 90° for a left-hand door. To facilitate such changes in position the pin K is provided with a loop K^1 by which it may be lifted and reinserted by a suitable hook or other implement introduced through an opening at m^4 in the cover M^1 , and a lug or projection J^6 on the upper face of the cam-plate J offers a convenient means of moving the latter into the desired position when released, by the application of the same or other implement.

An opening m^5 at the other end of the cover M^1 affords access to the spindle G and its stuffing-box, and the screw-plug N permits the introduction or removal of the piston F with its pitman G^3 and arm G^4 and the engagement of the arm with the square G^1 on such spindle.

The diagram, Fig. 9, shows the positions of the principal parts in various positions of the door, the full lines show the position when the latter is closed, as indicated by the strong dotted radial line L . When the door is swung as shown by the dotted line L^1 the roller C^4 is on the high point of the central ridge J^1 and the piston is fully drawn back in its cylinder ready to check a closing movement or a further opening movement. At L^2 the door is at 180° to the closed position, with the arm G^2 and piston F in the same position as when the door is closed, and at L^3 the door has been swung beyond the 180° as far as permitted by the contact of the roller C^4 with the end of the casing.

It is important that the arc described by the pin G^6 be greater than that described by the pin C^3 , or that the distance between these pins, as determined by the link H , shall be less than the distance between the shaft C and spindle G , or that the angular position of the two cranks thus

connected be such, relatively to each other, as to avoid a dead center due to alinement with each other and the shaft and spindle.

It will be noted that the liquid chamber and its checking mechanism are entirely separate and distinct from the closing mechanism, and capable of containing a large quantity of liquid which when the chamber is sealed by the plug N cannot escape by evaporation or otherwise and the hinge may be safely shipped while fully supplied with liquid without danger of leakage, and in positioning the hinge for service with either a right or left-hand door the checking mechanism requires no change and the liquid chamber need not be opened.

Modifications may be made in the forms and proportions of the parts within wide limits without departing from the invention, and parts may be used without the whole. The cam-plate J may be varied in shape, omitted, or formed in one with the slide D , or other means than that shown may be employed to vary the position of the ridge J .

I claim:

1. In a door-closer and check, a shaft adapted to be connected to the door, a spindle separated from and out of axial alinement with said shaft, means opposing the initial opening of such door, checking mechanism actuated by said spindle, and connections from said shaft to said spindle for imparting motion to the latter.

2. In a door-closer and check, a casing, a shaft mounted therein and adapted to be connected to the door, a spring in said casing acting upon said shaft and opposing the initial opening of such door, a spindle mounted in said casing, separated from and out of axial alinement with said shaft, checking mechanism actuated by the movements of said spindle, and connections from said shaft to said spindle for imparting motion to the latter.

3. In a door-closer and check, a casing having a spring chamber and a liquid chamber therein, a shaft mounted in said spring chamber and adapted to be connected to the door, a spring in said spring chamber and connections from said spring to said shaft, a spindle in said liquid chamber, separated from and out of axial alinement with said shaft, checking mechanism in said liquid chamber actuated by said spindle, and connections from said shaft to said spindle for imparting motion to the latter.

4. In a door-closer and check, a casing having a spring chamber and a liquid chamber therein, a shaft mounted in said spring chamber at one end of said casing and adapted to be connected to the door, a spring in said spring chamber and connections from said spring to said shaft, a spindle in said liquid chamber, mounted at the opposite end

of said casing, checking mechanism in said liquid chamber actuated by said spindle, an arm on said shaft and a pin carried thereby, a crank on said spindle and a pin thereon, 5 and a link pivotally joined at the ends to said pins.

5. In a door-closer and check, a casing, a shaft mounted vertically therein and adapted to be connected to a door, a slide 10 in said casing, an arm on said shaft arranged to move said slide, a spring in said casing acting upon said slide, a vertical spindle mounted in said casing and out of axial alignment with said shaft, checking 15 mechanism actuated by said spindle, a crank on the latter, and a link connecting said arm and crank.

6. In a device of the character set forth, a shaft adapted to be connected to a door, 20 a spring acting upon said shaft and arranged to exert its force in opposition to the movement of the door to a point in the arc of the swing of such door, and to exert its force to aid the further opening swing 25 of such door beyond such point, and means for varying the position of such point in such arc.

7. In a device of the character set forth, a shaft adapted to be connected to a door, 30 a spring acting upon said shaft, and arranged to exert its force in opposition to the movement of said shaft during the opening movement of the door to a point in the arc of the swing of such door, and 35 to exert its force to aid the further opening swing of such door beyond such point, means for varying the position of such point in such arc, and a checking mechanism arranged to check the movement of the door 40 from such point in either the closing or further opening movement.

8. In a device of the character set forth, a casing, a shaft mounted therein and adapted to be connected to a door, a spindle 45 mounted in said casing, a spring acting upon said shaft and arranged to exert its force in opposition to the movement of said shaft during the opening movement of such door to a point in the arc of the swing of 50 such door, and to exert its force to aid the further opening swing of such door beyond such point, and connections from said shaft to said spindle, arranged to move the latter and its checking mechanism to check the 55 movement of the door from such point in either its closing or further opening movement.

9. In a device of the character set forth, a casing, a shaft mounted therein and adapted 60 to be connected to a door, a slide, a spring opposing the movement of said slide from said shaft, an arm on said shaft adapted to engage said slide and to swing through an arc of approximately 180° with a corresponding swing of the door, said slide and 65

spring arranged to oppose such swing from either end of such arc to an indeterminate point therein, for service with either a right or left-hand door, and a laterally adjustable cam member on said slide. 70

10. In a device of the character set forth, a casing, a shaft mounted therein and adapted to be connected to a door, a slide, a spring opposing the movement of said slide from said shaft, an arm on said shaft adapted to engage said slide and to swing through an arc of approximately 180° with a corresponding swing of the door, said slide and spring arranged to oppose such swing from either end of such arc to an intermediate 75 point therein, means for varying the position of such point in such arc and a checking mechanism arranged to check such swing from such intermediate point to either end of such arc. 80

11. In a device of the character set forth, a casing, a shaft mounted therein and adapted to be connected to a door, a slide, a spring opposing the movement of said slide from said shaft, an arm on said shaft adapted to engage said slide and to swing through an arc of approximately 180° with a corresponding swing of the door, said slide and spring arranged to oppose such swing from either end of such arc to an intermediate 95 point therein, a spindle in said casing, a checking mechanism actuated by said spindle, a crank on said spindle, a link connecting said arm and crank, the latter arranged to be swung by said arm to check the 100 movement of such door from said intermediate point to either end of such arc. 90

12. In a device of the character set forth, a casing, a shaft mounted therein and adapted to be connected to a door, a slide mounted in ways in said casing, a spring opposing the movement of said slide from said shaft, an arm on said shaft carrying a roller adapted to engage said slide and to swing through an arc of approximately 180° with a corresponding swing of the door, said slide and spring arranged to oppose such swing from either end of such arc to an intermediate point therein, a ridge on said slide determining such intermediate point, and 110 means for varying the position of such ridge. 115

13. In a device of the character set forth, a casing, a shaft mounted therein and adapted to be connected to a door, a slide in said casing, a spring opposing the movement of said slide relatively to said shaft, an arm on said shaft arranged to engage said slide, a ridge on said slide in the path of said arm, and means for varying the position of said 120 ridge relatively to such arm. 125

14. In a device of the character set forth, a casing, a shaft mounted therein and adapted to be connected to a door, a slide in said casing, a spring opposing the movement of 130

said slide relatively to said shaft, an arm on said shaft arranged to engage said slide, a cam-plate movably mounted on said slide, a ridge on said cam-plate, and means for moving said cam-plate to vary the position of said ridge relatively to said arm.

15. In a device of the character set forth, a casing, a shaft mounted therein and adapted to be connected to a door, a slide in said 10 casing, a spring opposing the movement of said slide relatively to said shaft, an arm on said shaft arranged to engage said slide, a cam-plate movably mounted on said slide, a ridge on said cam-plate, means for moving 15 said cam-plate to vary the position of said ridge relatively to said arm, and a locking means engaging said cam-plate and slide.
16. In a device of the character set forth, a casing, a shaft mounted therein and adapted to be connected to a door, a slide in said 20 casing, a spring opposing the movement of said slide relatively to said shaft, an arm on said shaft arranged to engage said slide,

lugs on said slide, a cam-plate mounted in said lugs to slide transversely of said casing, 25 said cam-plate and adjacent face of said slide having grooves adapted to register, and a pin engaged in such grooves.

17. In a device of the character set forth, a shaft, a door-actuating mechanism connected thereto and arranged for service with either a right or left-hand door, a tapered square at the upper end of said shaft, and a reversible lever adapted to be secured to a door, said lever having a socket tapered inwardly from both faces of said lever and adapted to engage such square with either of such faces uppermost.

In testimony that I claim the invention above set forth I affix my signature, in presence of two witnesses.

HARRY J. WRIGHT.
